(57) **CLAIM**

The ornamental design for an electric bicycle frame, as shown and described.

DESCRIPTION

FIG. 1 is a usage state diagram of an electric bicycle frame. FIG. 2 is a perspective view of an electric bicycle frame showing my new design.

FIG. 3 is a front view of an electric bicycle frame.

FIG. 4 is a rear view of an electric bicycle frame.

FIG. 5 is a left side view of an electric bicycle frame.

FIG. 6 is a right side view of an electric bicycle frame.

FIG. 7 is a top view of an electric bicycle frame; and,

FIG. 8 is a bottom view of an electric bicycle frame.

The broken lines illustrate portions of the electric bicycle frame that form no part of the claimed design. The use of broken lines in FIG. 1 indicates that the environmental structure and form no part of the claimed design.
